SPECTACLE CASE

Fred G. Gay, Jr., and Raymond F. E. Stegeman, Greece, N. Y., assignors to Bausch & Lomb Optical Company, Rochester, N. Y., a corporation of New York

Application April 5, 1954, Serial No. 29,851

Term of patent 3½ years

(Cl. D57—1)

FIG. 1

FIG. 2

FIG. 3

To all whom it may concern:

Be it known that we, Fred G. Gay, Jr., and Raymond F. E. Stegeman, citizens of the United States and residents of the town of Greece, county of Monroe, and State of New York, have invented a new, original, and ornamental Design for a Spectacle Case, of which the following is a specification, reference being had to the accompanying drawing, forming a part hereof.

Fig. 1 is a front elevational view of a spectacle case in open position, showing our new design.

Fig. 2 is a front elevational view thereof, showing the case in closed position.

Fig. 3 is a rear elevational view thereof, showing the case in open position.

We claim:

The ornamental design for a spectacle case, substantially as shown.
